UNITED STATES PATENT OFFICE.

FRANKLIN E. ARNDT, OF GALION, OHIO, ASSIGNOR TO THE GALION IRON WORKS & MFG. CO., OF GALION, OHIO, A CORPORATION OF OHIO.

ELEVATOR OR CONVEYER.

Application filed November 4, 1922. Serial No. 599,078.

To all whom it may concern:

Be it known that I, FRANKLIN E. ARNDT, a citizen of the United States, residing at Galion, in the county of Crawford and State of Ohio, have invented certain new and useful Improvements in Elevators or Conveyers, of which the following is a specification.

This invention relates to conveyers or elevators, and particularly to portable conveyers such as are used for handling coke, coal, gravel, scrap iron, cement, etc., and are adapted particularly to be used for unloading materials into trucks, the particular elevator or conveyer which forms the subject of this application being intended for use with the horizontal drag conveyer described and illustrated in my pending application for patent, filed on the 4th day of November, 1922, Serial No. 599,077, and in Patent No. 1,437,581, granted on December 5, 1922.

The general object of this invention is to provide a conveyer or elevator of this type in which the elevator frame is supported by means of a superstructure on wheels, means being provided for raising or lowering the elevator frame so as to change the angle of its inclination, the construction being such as to permit the elevator or conveyer to be readily shifted from one position to another and arranged in the most convenient relation to the work to be done.

A further object of the invention is to improve upon elevators or conveyers of this type by providing a trough over which drag blades move, this trough having wear strips extending longitudinally thereof, upon which wear strips the blades travel, those margins of the blades which engage the wear strips being relatively wide.

A still further object is to so construct and mount the endless chains to which the blades are attached that the chains are disposed exterior to the trough, do not come in contact with the material being handled, and are not subjected to wear, the blades being supported entirely upon the wear strips and thus placing no downward strain upon the chains.

Another object is to provide improved means for connecting the blades to the endless chains and supporting the endless chains, and to provide a second trough over which the lower flight of the endless chain oper-

ates so that any dust or other material which may be carried over by the blades is discharged onto this second trough to be carried back again for re-elevation.

Still another object is to provide means for vertically guiding the elevator frame between the upright supports therefor, such means permitting the frame to be tipped to any reasonable angle.

A further object is to provide means whereby the slack may be taken up in the endless chains, and a trough section which is movable with the shaft carrying the sprocket wheels which are used to tighten up the chains.

Other objects will appear in the course of the following description.

My invention is illustrated in the accompanying drawings, wherein:

Figure 1 is a side elevation of an elevator constructed in accordance with my invention;

Figure 2 is a fragmentary longitudinal section thereof;

Figure 3 is a fragmentary top plan view of the elevator, the motor casing being partly broken away;

Figure 4 is a section on the line 4—4 of Figure 3;

Figure 5 is an elevation of the superstructure and the elevator tilting means;

Figure 6 is a fragmentary top plan view of the beam 16;

Figure 7 is a fragmentary perspective view of one of the elevator frame bars showing the guiding means 57.

Referring to these drawings, it will be seen that I have illustrated an elevator casing having an endless elevator operating therein, this elevator casing or frame being supported by a wheeled structure. The wheeled structure comprises, as illustrated in Figure 5, beams 10 having angle irons 11 bolted thereto and carrying the stub axles 12 and the wheels 13. The beams 10 are disposed on each side of angle iron uprights 14 which are held to the beams 10 in any suitable manner, as by the angle irons 15, and the upper ends of these uprights 14 are connected by transversely extending channel irons 16 connected by angle iron braces to the uprights, these beams 16 projecting beyond one of said uprights on one side. The extremities of the beams 10 are connected to the outwardly projecting 110

flange of the angle iron uprights 14 by means of braces 17. A bracket 18 is mounted upon one of the uprights 14 and the outer end of this bracket is supported by means of a vertical angle iron 19 which extends downward and is operatively connected to one end of the beams 10 and braced by a diagonal brace 20. The elevator frame is supported by means of a bail 21 connected to a pulley block 22.

Mounted upon the bracket 18 is a drum 23 operated by means of a gear wheel and a worm shaft 24 carrying a crank handle. Extending from this drum is a cable 25 which extends over a pulley 26 mounted in the projecting extremity of the beam 16, then the cable passes over a pulley or sheave 27, downward and around the pulley and block 22, then up again and over a second pulley 27^a, and then downward, and has its ends attached to a link 28 which extends upward from the yoke 21 and supports the pulley block. By this means it is obvious that the elevator frame may be raised or lowered to change its angle.

The elevator frame (see Fig. 4) comprises upper longitudinally extending angle irons 29 and lower longitudinally extending angle irons 30, these angle irons being connected at intervals by vertical plates 31, these vertical plates having angle irons 32 attached to them, and attached to these angle irons are transverse bracing angle irons 33, upon which is supported the trough 34, this trough having upwardly turned side walls, these side walls being spaced from the plates 31. Attached to the angle irons 29 are inwardly extending brackets 35, and attached to these brackets are longitudinally extending sheet metal walls 36, the upper margins of which are outwardly flared, the lower portions of these walls being in alignment with the upwardly turned walls of the trough 34 and the lower edges of these walls 36 being spaced from the upper edges of the side walls of the trough.

Extending through suitable bearings in the lower end of the elevator frame is a transverse shaft 37 carrying sprocket wheels 38, (see Fig. 2) and operatively supported in suitable bearings in the upper end of the elevator frame, as will be later explained, is a transverse shaft 39 carrying sprocket wheels 40. Operating over these sprocket wheels 38 and 40 are the endless chains 41, the upper flights of which are disposed coincident with the slot or space between the lower edges of the walls 36 and the upper edges of the side walls of the trough 34. Operating within the trough 34 are transverse blades 42, the extremities of which are riveted to inwardly extending flanges attached to links 43. The lower edges of the blades are angularly bent and extend toward the lower end of the elevator.

Attached to the angle irons 30 is a lower trough 44 which is disposed just below the lower flight of the blades 42. The upper face of the trough 34 is provided with a plurality, as for instance three, wear strips 45 which are connected in any suitable manner to the bottom of the trough, and it is over these wear strips that the blades 42 travel so that no wear comes upon the bottom of the trough but only upon the wear strips. The blades, having their angular lower edges traveling over these wear strips, are fully supported and as a consequence no downward pull comes upon the chains 41, nor does any wear come on the side walls of the trough 34 nor upon the shanks of the blades which are supported above the upper edges of the trough walls, the sole function of the chains being to drag the blades up the trough 34 and down the trough 44. A cross piece 46 extends across the lower end of the trough above the path of movement of the blades and just below this cross piece is pivoted a gate 47 which normally bears upon the wear strips but swings inward to permit the blades to pass and then as soon as a blade has passed drops downward again upon the wear strips and upon the bottom of the trough, the lower edge of this gate being cut away to fit over the wear strips.

The shaft 39 is preferably mounted for movement longitudinally of the elevator frame so as to take up slack in the chains 41, and to this end plates 48 are riveted to the downwardly extending flanges of angle irons 29 at the upper ends thereof and form guides between which the cross heads 49 slide, these cross heads being provided with bearings for the shaft 39. Each cross head has attached to it a rearwardly extending screw 50, which screw passes through a yoke 51 or cross bar and engaging this screw is a nut 52. By adjusting this nut, the cross heads 49 may be shifted longitudinally to thus take up any slack. Preferably the upper end of the trough 34 will be formed of a trough-shaped section 53 which will embrace the trough and overlap it and which will be attached to the cross heads 49 so that as the cross heads and shaft 39 are moved rearward this shiftable cross section 53 will also be moved rearward.

Pivoted to the lower angle irons 30 is a chute 54, upon which the elevator discharges and which may be used to guide material downward into a truck, this trough being supported by braces 55 having adjustable connections with the angle irons 30. Preferably angular members 56 will be attached to each upper angle iron 29 to project laterally therefrom and extend on each side of the upright 14. Attached to these angular members 56 on the confronting faces thereof are rounded abutments 57 which are spaced from each other sufficiently to loose

ly embrace the flanges of the uprights 14 and thereby guide the elevator in its vertical movement, while at the same time the rounded faces permit the elevator to be 5 turned through a considerable angle. The elevator frame is furthermore supported by means of bracing bars 58 of angle iron which are each pivoted to one extremity of an angle iron 11, the other ends of these angle 10 irons 58 being pivotally connected to plates 59 attached to the lower frame bars 30 of the elevator frame. Thus these braces may be shifted to any angle in accordance with the elevation of the elevator and its angle.

15 For the purpose of operating the elevator, an electric motor is used, mounted within a motor casing 60 which is attached to the frame of the elevator above the uprights 14.

The motor, which is ordinarily seven and a 20 half horsepower, carries on its shaft a gear wheel 61 shown as meshing with a gear wheel 62, the shaft of which carries a pinion 63, in turn meshing with a relatively large gear wheel 64, this gear wheel 64 being fast upon

25 a shaft 65 which carries a pinion 66, in turn engaging a pinion 67 mounted upon a shaft 68 which extends through the motor casing and carries on it a sprocket wheel with which a sprocket chain 69 engages, this

30 sprocket chain extending around a sprocket wheel 70 mounted upon the shaft 39 and thus the endless elevator is driven. The motor is, of course, to be connected to any suitable source of electric power by flexible

35 connections, plugs, etc., not necessary to describe or illustrate, as this is common in the art. I, of course, do not wish to be limited to the particular gearing which I have described, as it is obvious that other gearing

40 might be used, nor do I wish to be limited to the details of construction and arrangement of parts as illustrated and described except as defined in the appended claims.

The particular advantages of this elevator 45 are as follows: The elevator may be raised or lowered without any tendency of the elevator frame to swing longitudinally. In other words, the bail which supports the elevator frame is always disposed in alignment

50 with the uprights 14. This is secured by the engagement of the members 57 on each side of the uprights 14. If it were not for these members, there would be a tendency of the elevator frame to slew forward and

55 there would be difficulty in keeping the uprights in proper position. This is, of course, further prevented by the braces 58. When the elevator is turned to a horizontal position, it may be readily trundled to any de-

60 sired point and may be readily adjusted to the exact position required for operation. The elevator frame may then be raised or lowered to the requisite degree to permit the discharge of material into trucks, cars,

One of the particular advantages due to the details of construction described is that there is no wear upon the trough 34 for the reason that the drag blades 42 rest upon relatively heavy and thick rails or wear 70 strips 45. Furthermore, this permits the deposit on the face of the trough of a small amount of powdered material, such as coal, which aids the blades to slide over the face of the trough. It will further be noted that 75 this construction takes away all strain, due to the weight of the blades, from the chains 41 so that these chains are simply under a pulling strain, and furthermore it will be seen that the shanks of the attachment links 80 extend through the slots formed between members 36 and the upwardly turned side walls of trough 34 without touching the edges of these side walls at all so that there is no wear on these side walls. The chains 85 are disposed entirely exterior to the trough and, therefore, do not come in contact with the material being elevated and do not become clogged or loaded with dirt which would obstruct the free movement of the 90 chains and which would get into the links and impede their flexibility. The construction of the elevator frame is such that it is very light and yet very strong and, as before remarked, all dust or material that may be 95 carried down to the blades is caught on the lower trough and carried downward with the blades and discharged at the forward end of the elevator, where it is again likely to be picked up and carried up over the 100 trough 34 and discharged into the truck or other receptacle.

This elevator is designed to be used with the conveying mechanism illustrated in my pending application, Serial No. 599,077 filed of even date herewith, this elevating mechanism being driven from shaft 65 by means of a sprocket wheel 71 loose upon this shaft and adapted to be thrown into or out of operative engagement therewith by 110 means of a clutch member 72 having a clutch operating lever 73. It will be obvious, however, that the elevator may be used disassociated from the conveyer.

I claim:—

1. A conveyer including a trough having upturned side walls and side walls supported in alignment with and above the side walls of the trough, the side walls of the trough and the second named side walls 120 together defining elongated slots, blades operating over and resting upon the bottom of the trough and having shanks extending through said slots and beyond the side walls and supported by the blades in 125 spaced relation to the walls of the slots, endless elements disposed exterior to the walls and connected to said blades, and means for supporting and driving the endless elements.

2. A conveyer frame comprising laterally disposed upper and lower longitudinal members, vertical members connecting the longitudinal members on each side, transverse members connecting the vertical members, an upper trough resting upon said transverse members and narrower than the space between the vertical members, said trough having side walls, blades operating over and supported by the floor of the trough and having shanks extending out over said side walls and out of contact therewith, and endless elements disposed exterior to the side walls and operatively connected to said blades.
3. A conveyer including a frame comprising upper and lower longitudinally extending angle irons on each side, vertical members connecting the upper and lower angle irons of each pair, transverse members connected to the vertical members, a trough having upwardly extending side walls resting upon said transverse members, vertical walls operatively supported upon the longitudinal members and disposed in vertical alignment with the walls of the trough but spaced therefrom to provide slots, blades operating over and supported by the floor of the trough and having shanks extending through said slots but out of contact with the slot walls, endless elements disposed exterior to said walls and opposite said slots and to which the shanks are operatively connected, and means for supporting and operating said endless elements.
4. A conveyer including a conveyer frame comprising upper and lower longitudinally extending angle irons on each side, vertical elements connecting the angle irons of each pair, transverse members connected to the vertical members, a trough supported upon the transverse members and having upwardly extending side walls, the width of the trough being less than the distance between the vertical members, side walls disposed in vertical alignment with the side walls of the trough but spaced therefrom to provide slots, brackets connecting said last named side walls to the upper angle irons, blades operating over and supported entirely by the floor of the trough and having shanks extending through said slots but out of contact with the slot walls, endless elements connected to said shanks and disposed exteriorly of the side walls but be-
- tween the side walls and the upper longitudinal members, and means for supporting and operating the endless elements.
5. In a conveyer and elevator of the character described, a wheeled frame including uprights and transverse connecting members, a conveyer frame disposed between said uprights and movable vertically independently of the uprights, links pivotally connected to the wheeled frame and to the conveyer frame, a bail pivotally connected to the conveyer frame, hoisting mechanism connected to the bail whereby the elevator may be raised or lowered, and guides loosely embracing the uprights mounted on the conveyer frame, said guides having rounded faces confronting the uprights permitting the conveyer frame to be turned to a plurality of angles to the uprights.
6. A portable conveyer including a wheeled supporting frame, the frame comprising a transverse beam, stub axles secured to said beam and projecting laterally therefrom, wheels on the stub axles, uprights connected to said beam, a cross bar connecting the upper ends of said uprights, an elevator frame disposed between the uprights, a bail pivotally connected to the elevator frame, a block and tackle connection between the bail and the cross bar of the frame and including a cable, a winding drum mounted upon the wheeled supporting frame and to which said cable is connected, and links pivotally connected to the wheeled frame and to the elevator frame.
7. In an elevator and conveyer, an elevator frame having a longitudinally extending trough, blades operating over the trough, endless elements to which the blades are connected, means for supporting and driving the endless elements including a shaft at the upper end of the trough, wheels mounted thereon and over which the endless elements pass, said shaft being longitudinally movable with relation to the trough, means for shifting said shaft longitudinally to thereby take up slack in the endless elements, and a trough section disposed beneath the upper end of the first named trough and forming a continuation thereof and operatively connected to move longitudinally with said shaft.

In testimony whereof I affix my signature.

FRANKLIN E. ARNDT.
